UNITED STATES PATENT OFFICE.

WYLE T. WILSON, OF PHILADELPHIA, PENNSYLVANIA.

CLOTH-BOARD MADE OF PULP MATERIAL.

1,112,957.

Specification of Letters Patent.

Patented Oct. 6, 1914.

Application filed November 6, 1913. Serial No. 799,538.

To all whom it may concern:

Be it known that I, WYLE T. WILSON, a citizen of the United States, residing at Philadelphia, in the county of Philadelphia and State of Pennsylvania, have invented 5 certain new and useful Improvements in Cloth-Boards Made of Pulp Material; and I do hereby declare the following to be a full, clear, and exact description of the invention, such as will enable others skilled in the art to which it appertains to make and use the same.

This invention relates to boards especially adapted for the wrapping of cloth and other fabrics thereon, and has for its object to produce a board of this character from pressed paper or other pulp which will be light in weight, and yet sufficiently strong and rigid to withstand the strains to which it would 20 ordinarily be subjected, and also to provide such board with rounded or cushioned edges to prevent injuring the fabric when dropped against sharp edges or other obstructions.

With these and other objects in view, the 25 invention consists in the novel details of construction hereinafter more fully described and particularly pointed out in the claims.

Referring to the accompanying drawings forming a part of this specification, in which 30 like numerals designate like parts in all the views:—Figure 1 is a perspective view of a board constructed in accordance with this invention; Fig. 2 is a cross sectional view taken on the line 2—2 of Fig. 1; Fig. 3 is a 35 sectional view of a modified form of my board provided with cushioned edges; and, Figs. 4, 5, 6, 7 and 8 are plan views showing modified arrangements of the strengthening ribs with which my board is provided.

40 1 indicates the body of my board, which may be made of any suitable material, but preferably of pressed paper pulp. This pulp is conveniently had by grinding waste paper and other scrap material found in factories employing large quantities of paper, and after the same is ground, I preferably unite the same with a suitable binder, such as a liquid containing a glue or cement-like substance, and in some cases, I may add a 45 filler thereto in order to give body and strength to the board. A convenient filler for some cases is found in plaster of Paris. In other cases, a filler having Portland cement as a base is found to be efficient. In 50 other cases, the glue itself is found sufficient, and especially when the board is sub-

jected to high pressure, as is desirable in most cases.

In order that the board shall be as light as possible, consistent with sufficient strength, 50 I provide the body of the same with a plurality of strengthening members as shown in the drawings. These strengthening members are preferably so located as to form an integral bracing structure. That is to say, 55 in Fig. 1, for example, the member 3 extends through the center of the board from end to end, and the member 4 crosses the same at right angles, so that the two members effectually brace the board while the web portion 5 further stiffens it. In order to further strengthen and stiffen the board, and yet not have it too heavy in the form shown in Fig. 1, I run the diagonal braces 6 and 7 across the web portion 5, and the whole furnishes an exceedingly strong, stiff and light 75 board.

In the form shown in Fig. 4, the parallel zigzag bracing members 8 and 9 run from side to side of the board, being integral with 80 the web portion 5 and separated as shown. Crossing the members 8 and 9 are the similar zigzag members 10 and 11, likewise integral with the web portion 5, and this structure also results in a stiff and strong 85 board of sufficient lightness to make the same practical.

In the form shown in Fig. 5, the diagonal parallel members 12 and 13 are integral with the edges of the board and with the web 90 portion 5. They are crossed by similar diagonal members 14 and 15 which are likewise integral with the edge members of the board and the web portion 5. In addition to these said members, the parallel members 95 16 and 17 cross from edge to edge of the board through its center and are integrally united with the above mentioned bracing members. These members alone serve to stiffen and strengthen the board as in the 100 cases above, while the additional members 18 and 19 at each end connected by the parallel members 20 and 21 further add stiffness and strength to the board. The diagonal member 12 is braced by the parallel 105 members 22 and 23, and the diagonal member 13 is braced by the parallel members 24 and 25. The diagonal member 15 is braced by the parallel members 26 and 27, and the diagonal member 14 is braced by the parallel 110 members 28 and 29.

In the form shown in Fig. 6, the central

member 30 crosses from side to side of the board, while the longitudinal central member 31 stops short of the end edges and meets at each end the inclined members 32, as shown. The web 5 not occupied by the above mentioned members is further braced by the circular ribs 33 as shown.

In the form shown in Fig. 7, two parallel central members 35 and 36 extend from end to end of the board, and these are crossed at intervals by the parallel members 37 and 38 which extend from side to side of the board and all of said members are integral with the edge member 54, while the web member is omitted, or provided with holes 55 as shown.

In the form shown in Fig. 8, two diagonal members 40 and 41 cross the web portion 5 at the center, and the central member 42 crosses said web portion from side to side of the board, as shown. The members 40 and 41 are further braced by the circular members 43 which are integral with said members 40 and 41 and also with the side edges of the board, as shown. The said members 43 are further provided with the diametrical bracing members 44 and 45, as illustrated. In addition to the above, the said members 40 and 41, as well as the central member 42, are braced by the circular members 46 which are integral with the said members 40, 41 and 42, as well as with the side edges of the board. The said circular members 46 are further braced by the diametrically extending members 47, as will be clear from the drawings.

In the modified form of structure shown in Fig. 3, the body 50 of the board is made of pulp or multiple layers of pulp material 40 which may be bound or fastened together by any suitable means, forming a board of the same general characteristics as those above described. In addition to this, the central layers of pulp are extended at the edge as indicated at 51, and passing over the whole body portion is a piece of straw board or paper 52 constituting cushioned edges 53 firmly braced by the projecting edges 51 of the central layers.

In all of the forms disclosed, the extreme end and side edges 54 of the boards are curved or rounded, as shown, so that if the cloth, lace, silk or other delicate fabric which is ordinarily wrapped around these boards is dropped on a sharp corner, the said fabric

will not be injured. The soft nature of the pulp greatly aids in this result. It will also be observed that in all of the forms, the bracing ribs have been so disposed as to give a maximum strength with a minimum lightness. It is obvious, however, that those skilled in the art may vary the disposition of the ribs and other features of this invention without departing from the spirit thereof, and therefore I do not wish to be limited to the above disclosure except as may be required by the claims.

What I claim is:

1. A cloth board of pulp material comprising a web member; a rounded edge member; and a plurality of bracing members integral with said web and edge members, substantially as described.

2. A cloth board of pulp material comprising a web member; a plurality of rounded edge members integral with said web member; and bracing members extending from side to side and from end to end of said board integral with said web and edge members, substantially as described.

3. A cloth board of pulp material comprising a web member; rounded edge members on the sides and ends of said board integral with said web member; a plurality of bracing members crossing each other at the center of said board extending from end to end and from side to side of said board and integral with said side and end members and said web member; and additional bracing members integral with said first named bracing members and with said edge and web members, substantially as described.

4. A cloth board formed of layers of pulp material provided with a web member; a rounded edge and with bracing members associated with said web member, substantially as described.

5. A cloth board formed of pulp material provided with a continuous edge member and with bracing members associated with said edge member, substantially as described.

In testimony whereof I affix my signature in presence of two witnesses.

WYLE T. WILSON.
